GRENADE FUSE

Morton Burden, Jr., Sewickley, Pa.

Application March 30, 1945, Serial No. 585,758

3 Claims. (Cl. 102—71)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to grenades and more particularly to time fuzes for grenades.

A tactical need exists in combat operations for a grenade device which may be fired from a rifle or thrown by hand and which is armed so that detonation will occur either on impact or a few seconds after impact. Furthermore, it is well recognized that if the impact detonation does not occur, for some reason, an additional means for detonating the grenade upon failure of the initial detonating means would add considerable military usefulness to the device.

It is, therefore, a prime purpose of this invention to provide such an auxiliary detonating means, which will automatically function to detonate the grenade upon the lapse of a brief delay period should the grenade fail to detonate on impact.

Another object of this invention is to provide a novel and improved grenade which may be fired from a rifle or thrown by hand and which has desirable time delay features.

A further object of this invention is to provide a grenade fuze which will be armed for detonation upon impact or which will detonate at the end of a delay period after impact if detonation has not occurred at impact.

Further objects and advantages of the invention will appear from the following description and claims, and from the accompanying drawings, wherein:

Figure 1 is a fragmentary longitudinal sectional view taken on the line 1—1 of Fig. 2 showing the detailed structure of a grenade fuze according to this invention;

Figure 2 is a longitudinal sectional view taken on line 2—2 of Figure 1, and disclosing the arming means for the grenade fuze;

Figure 3 is an enlarged cross-sectional view of the fuze taken on line 3—3 of Fig. 1; and

Figure 4 is a cross sectional view of the fuze taken on line 4—4 of Fig. 1.

Referring to the drawings, 1 designates a tubular sleeve member adapted to be appropriately mounted on a conventional rifle grenade launcher for propulsion thereby in a well known manner; or to be held in the hand for manual propulsion. Sleeve member 1 is provided with an aperture end wall 2 in which a fuze member is secured. Fuze member 3 comprises a threaded body portion 4 adapted to be screwed into the internally threaded 55

2

end of a standard hand grenade 5 with the major portion of body portion 4 extending into the grenade. At the inner end of body portion 4 is a cap member 6 within which is provided a booster charge 7, which, when detonated, sets off the main fragmentation charge of the grenade.

The outer portion of fuse member 3 comprises a mating element 8 which is secured to body portion 4 by conventional flange elements 9 and 10 provided respectively on element 8 and body portion 4, through which a plurality of bolts 11 are engaged in a manner well known in the art.

End wall 2 of sleeve 1 is clamped between grenade 5 and flange 10 for securement thereof, but 15 may be welded or otherwise secured to body portion 4.

Cooperating internal recesses are provided in element 3 and body portion 4 to form a cavity 12. Clamped between element 8 and body portion 20 4 and extending transversely across cavity 12 is a fusible strip 13 of Celluloid or other readily combustible material which carries a weighted striker member 14. An axial flash bore 16 is provided, communicating with booster charge 7, and 25 having a primer member 17 positioned at the top end thereof in position to be detonated by striker member 14.

A side bore 18 is provided in fuse member 3, into which one end of fusible strip 13 extends. Bore 30 18 is inwardly directed at the upper end of element 3 so as to communicate with a primer member 19 centrally positioned at the top of fuze member 3. Bore 18 contains a powder train or other well known combustible fuze timing means.

35 When primer member 19 is detonated the powder train, or other similar fuze train, in bore 18 is ignited, and after an initial period, ignites fusible strip 13. The combustion of strip 13 releases striker member 14, during flight of the grenade, 40 thus arming the grenade for impact operation, whereby upon impact of the forward end of the grenade against the ground or other object member 18 will strike primer 17 to detonate same. The detonation of primer 17, flashing through bore 45 16 sets off booster charge 7 and thereby causes the explosion of the main fragmentation charge, not shown, contained in the grenade body 5.

Should fusible strip 13 fail to release striker member 14 or should primer member 17 fail to be detonated by said striker member, after a delay period, continued combustion of the powder train in side bore 18 will ultimately cause booster charge 7 to be exploded. The time required for powder train 18 to reach the booster 7 can be about 6 seconds or slightly greater than the maxi-

mum time period for flight of the grenade when thrown or propelled from a grenade launcher.

Tubular sleeve member 1 is provided with a pin 20 upon which is pivotally mounted a striker arm 21 provided with a firing pin element 22. A coil spring 23 is wound around pin 20 and has one end thereof in engagement with the rear side of striker arm 21, the other end of said spring 23 bearing against the inner wall surface of sleeve member 1. Coil spring 23 normally biases striker arm 21 toward a striking position whereby firing pin 22 will strike primer member 19 when arm 21 is released. Striker arm 21 is normally maintained in safe position by a hooked lug member 24 suitably connected to an outer sleeve member 25 and extending through a slot 26 in sleeve member 1 to hold arm 21 in safe position. Slot 26 is of sufficient length to permit lug 24 to move out of engagement with arm 21 when sleeve 25 is moved rearwardly with respect to sleeve 1.

A safety pin member 27 normally extends transversely through sleeve members 1 and 25 in obstructing position with respect to striker arm 21. At one outer end thereof, pin member 27 is provided with a longitudinally extending arm portion 28 and at the other outer end thereof is provided with a removable cotter pin 29. A strong compression spring 30 is positioned around pin 27, bearing between arm portion 28 and sleeve member 25 and biases pin 27 to an extracted position with respect to sleeve members 1 and 25. When cotter pin 29 is removed, as would be the case for propulsion of the grenade device, pin 27 will be ejected by spring 30 when the user releases his grasp on arm 28.

A further transverse pin member 31 is provided, which extends through sleeve members 25 and 1, elongated slots 32, being provided in sleeve member 25 to permit sufficient rearward movement of sleeve 25 with respect to sleeve 1 to release lug 24 from holding engagement with striker arm 21. A coil spring member 33 is wound around pin member 31 and has one end thereof in anchored engagement with the inside surface of sleeve 1, the other end thereof normally passing through an elongated slot 34 in sleeve 1 and through an appropriate opening therefor in sleeve 25. Slot 34 is of sufficient length to permit rearward movement of sleeve 25 with respect to sleeve 1, sufficiently to release striker arm 21. Coil spring 33 normally biases sleeve 25 to this rearward position but said sleeve is normally held in safe position by pin 27. However, when it is desired to throw the grenade device by hand, cotter pin 29 is removed, as described above, causing pin 27 to be released for ejection by spring 30 as soon as the grenade device leaves the thrower's hand. Spring 33 can then move sleeve 25 rearwardly to release striker arm 21.

When the grenade device is to be fired from a rifle grenade launcher, pin member 31 is extracted by pulling outwardly on its extraction ring 35 and spring member 33 is thus rendered inactive. Immediately before firing, cotter pin 29 is removed, causing pin 27 to be ejected by spring 30. When propelled from a rifle, setback of sleeve 25 releases striker arm 21, causing detonation of primer 19. There is sufficient frictional engagement between sleeves 1 and 25 to prevent accidental release of the striker arm 21 prior to the grenade being propelled from the launcher.

It is thus apparent that the grenade device disclosed in the foregoing description is adapted to be either fired from a rifle or to be thrown, and that in either case explosion of the grenade will occur either on impact or after a first time period, that is, in the event of the grenade failing to explode on impact, it will be set off after a predetermined time interval from the moment of launching.

While a specific embodiment of a grenade device has been disclosed, it will be understood that various modifications within the spirit of the invention may occur to those skilled in the art. Therefore, it is intended that no limitations be placed on the invention other than as defined by the scope of the appended claims.

I claim:

1. A multi-purpose grenade fuze and launching device adapted to be either manually thrown or fired from a rifle comprising a cylindrical member constructed and arranged to be mounted on a rifle for launching, and also to be grasped as a handle for throwing, a cylindrical sleeve frictionally mounted thereon for longitudinal sliding movement thereon, said cylinder member having an apertured wall at one end thereof, a body fastened to said wall and extending through the aperture thereof and having means for engaging a grenade body, a booster charge carried by said body, first primer means carried by said body, a time delay powder train extending from said first primer means to said booster charge, a second primer means carried by said body for exploding said booster charge directly, inertia means forwardly movable on impact to detonate said second primer means, combustible means restraining said inertia means and connected to said delay powder train intermediate the ends thereof, and means operable by said cylindrical sleeve for detonating said first primer means.

2. The invention recited in claim 1, including a spring actuated firing pin for said first primer means normally restrained by said cylindrical sleeve and releasable on sliding movement of said sleeve on said cylindrical member to detonate said first primer, spring means urging said sleeve toward firing position and manually controlled means for retaining said sleeve in said normal position until the cylinder is released from the hand.

3. The invention recited in claim 2, said spring means being mounted in said cylindrical member to obstruct loading thereof on a rifle, means for readily removing said spring means to permit loading of said cylindrical member on a rifle, and means operable by the effect of set back on said cylindrical sleeve to slide same into release position to detonate said first primer.
